UNITED STATES PATENT OFFICE.

CHARLES S. ROSS, OF LOS ANGELES, CALIFORNIA.

BULL OR CALF WHEEL FOR WELL-RIGS.

1,235,504.

Specification of Letters Patent. Patented July 31, 1917.

Application filed June 19, 1916. Serial No. 104,505.

To all whom it may concern:

Be it known that I, CHARLES S. Ross, a citizen of the United States, residing at Los Angeles, in the county of Los Angeles and 5 State of California, have invented new and useful Improvements in Bull or Calf Wheels for Well-Rigs, of which the following is a specification.

This invention relates to bull or calf 10 wheels for well rigs, and pertains especially to an improvement in lagging, and the means of securing the same to the coiling drum. To prevent excessive wearing of the line wound upon a bull or calf wheel drum, 15 it is found desirable to place a cushion lagging upon the coiling drum. For this purpose the coiling drum has been covered with longitudinally extending lagging ropes or cables. Hitherto with such constructions it 20 has been difficult to prevent fraying of the ends of the lagging ropes and to secure the same to the drum. It is an object of my invention to provide means for securing the ends of the lagging ropes to the drum, and 25 at the same time cover them to prevent fraying.

I have illustrated an embodiment of my invention in the accompanying drawing, in which:

30 Figure 1 is an elevation of a calf wheel, portions thereof being broken away and shown in section.

Fig. 2 is a section as seen on the line 2—2 of Fig. 1.

35 Fig. 3 is a section as seen on the line 3—3 of Fig. 1.

Fig. 4 is a fragmentary section showing the means of securing the ends of the lagging ropes together.

40 Referring more particularly to the drawing, I have shown my invention applied to a calf wheel in which a hollow cylindrical coiling drum or shaft, preferably of metal, is indicated by 5. Secured to the ends of 45 this shaft are gudgeons 6 and 7 suitable for mounting the shaft in journal boxes. The gudgeon constructions are similar and are preferably separate members from the shaft 5. Gudgeon 6 has a cylindrical portion 8 50 mounted within the bore of the shaft 5, and is secured thereto by means of set screw 9. Any other suitable construction may be used as this part of the structure is not material to my invention.

55 Mounted upon the shaft 5 adjacent the gudgeon 6 is a drive wheel 10 which is

preferably of the usual construction, comprising a hub and tangential spokes bolted thereto. A band 11 is shrunk upon the shaft 5 between the end thereof and the 60 drive wheel 10. A clearance drum 12 is mounted upon the shaft 5 adjacent the drive wheel 10, and is of a special construction later described. At the opposite end of the shaft 5 is a flange member 13. The space intermediate the flange member 13 and the clearance drum comprises the coiling drum indicated by 14, and upon which the lagging is mounted.

The lagging is tubular in form covering 70 the drum and is preferably comprised of ropes 15 arranged longitudinally and of a length slightly greater than the distance between the clearance drum 12 and the flange member 13. The ends of the ropes 15 are 75 secured to each other by weaving about them threads or strings 16 and 17. The intermediate portion of the lagging is wired by wires 18 and 19 which are threaded through each of the ropes and extend peripherally of the drum 14.

The clearance drum comprises a cylindrical portion 20 upon which the inactive 85 part of the line for the well rig is to be coiled. Formed upon the end of the cylindrical member 20 in a flange 21 which has formed therein a slot 22 for the cross-over line. The clearance drum is formed in two sections divided radially along a diameter as indicated by 23. For the purpose of 90 clamping the sections of the clearance drum upon the shaft 5 and of fixedly securing the same to the shaft, I have provided tangentially extending apertures for the purpose of receiving bolts 24. Recesses 25 are 95 formed in line with the longitudinal axes of the apertures and upon the surface of the cylindrical portion 20 of the drum. Within these recesses are disposed the heads and nuts of the bolts. It is obvious that by this 100 construction the clearance drum may be tightly clamped to the shaft 5. The bore of the clearance drum is counterbored as indicated by 26, and an inwardly extending tongue 27 is formed at the outer edge thereof. This tongue is for the purpose of engaging the ropes 15 adjacent the ends. The ends of the ropes lie within the counterbore 26.

The flange member 13 comprises a cylindrical portion 28 and a flange 29. The flange member is divided diametrically at

- 30 forming two parts. Means is provided for clamping the flange member to the shaft 5 and comprises radially extending lugs 31, pairs of which register with one another 5 and are bored to receive bolts 32. A counterbore 33 is formed in the flange member 13 and an inwardly extending tongue 34 for the purpose of gripping the ends of the ropes.
- 10 In assembling the calf wheel the lagging is placed in position upon the shaft 5 and the clearance drum 12 mounted thereon within the tongue 27 gripping the ends of the rope. The flange member 13 is then 15 mounted upon the opposite end gripping the other ends of the ropes. By tightening the bolts 24 and 32 on the clearance drum and flange members respectively, the lagging is firmly secured to the shaft and the ends 20 protected from fraying.

What I claim is:

1. In a wheel construction for well rigs, the combination of a coiling drum; a tubular lagging disposed thereon; divided flange 25 members mounted thereon, one adjacent each end of said drum, said members having bores in which said drum is disposed, and means to grip the ends of said lagging between said drum and flange members.
- 30 2. In a wheel construction for well rigs, the combination of a coiling drum; a tubular lagging disposed thereon; divided flange members mounted thereon, one adjacent each end of said drum, said members having 35 bores in which said drum is disposed, and inwardly extending tongues to grip the ends of said lagging between said drum and flange members.
3. In a wheel construction for well rigs, 40 the combination of a coiling drum; a lagging for said drum comprised of longitudinally extending ropes; and flange members mounted thereon, one adjacent each end of said drum, said members having bores in 45 which said drum is disposed, and inwardly extending tongues to grip the ends of said lagging.
4. In a wheel construction for well rigs, 50 the combination of a coiling drum; a lagging for said drum comprised of longitudinally extending ropes; segmental flange members mounted thereon, one adjacent each end of said drum, means for securing the segments of said flange members together, said flange 55 members having bores in which said drum is disposed, and tongues extending inwardly therefrom to grip the ends of said lagging.
5. In a wheel construction for well rigs, 60 the combination of a coiling drum; a tubular lagging disposed thereon; a divided clearance drum mounted thereon, said clearance

drum having a bore in which said coiling drum is disposed, and a tongue extending inwardly from said bore to grip an end of said lagging between said coiling drum and said clearance drum; a divided flange mounted upon the opposite end of said drum, said flange having a bore in which said drum is disposed, and an inwardly extending tongue to grip the other end of said 65 lagging between said drum and flange.

6. In a wheel construction for well rigs, the combination of a coiling drum; a lagging covering said drum comprised of longitudinally extending ropes; a clearance 75 drum mounted thereon, said clearance drum having a bore in which said coiling drum is disposed, and a tongue extending inwardly from said bore to grip the ends of said ropes; a flange mounted upon the opposite end of said drum, said flange having a bore in which said drum is disposed, and an inwardly extending tongue to grip the other ends of said ropes.

7. In a wheel construction for well rigs, 85 the combination of a coiling drum; a tubular lagging disposed thereon; a segmental clearance drum mounted thereon, means for clamping the segments of said clearance drum to said coiling drum, said clearance 90 drum having a bore in which said coiling drum is disposed, and a tongue extending inwardly from said bore to grip an end of said lagging; a segmental flange mounted upon the opposite end of said drum, 95 means for clamping the segments of said flange to said coiling drum, said flange having a bore in which said drum is disposed, and an inwardly extending tongue to grip the other end of said lagging.

8. In a wheel construction for well rigs, 100 the combination of a coiling drum; a lagging covering said drum comprised of longitudinally extending ropes; a segmental clearance drum mounted thereon, means for 105 clamping the segments of said clearance drum to said coiling drum, said clearance drum having a bore in which said coiling drum is disposed, and a tongue extending 110 inwardly from said bore to grip the ends of said ropes; a segmental flange mounted upon the opposite end of said coiling drum, means for clamping the segments of said flange to said coiling drum, said flange having a bore in which said drum is disposed, 115 and an inwardly extending tongue to grip the other ends of said ropes.

In witness that I claim the foregoing I have hereunto subscribed my name this 29th day of May, 1916.

C. S. ROSS.
